UNITED STATES PATENT OFFICE.

RUDOLPH FERENTZI, OF NEWARK, NEW JERSEY.

HEATED BED.

1,395,912.

Specification of Letters Patent.

Patented Nov. 1, 1921.

Application filed January 28, 1918. Serial No. 214,152.

To all whom it may concern:

Be it known that I, RUDOLPH FERENTZI, a subject of the Emperor of Austria, residing at No. 301 Washington avenue, city of Newark, in the county of Essex and State of New Jersey, have invented a new and useful Heated Bed, of which the following is a specification.

This invention relates to certain new and useful improvements in beds and more particularly to those which are adaptable for use for children, sick or elderly people.

The main object of the invention is the provision of heat to the bed, so that the person occupying the same can be kept comfortably warm.

Another object of the invention is the provision of a cover support for holding the bed cover away from the person occupying the bed.

Still another object of the invention is the provision of a heated bed in which a continuous circulation of warm air may be maintained at any desired temperature suitable for the occasion.

A further object resides in the fact that the bed coverings are supported above the body of the person occupying the bed and therefore allows for freedom of movement beneath the same without any danger of displacement.

With these and other objects in view, which will be apparent from the following description, I wish it understood that while I have shown in the accompanying drawings the preferred embodiment of my invention, certain changes or variations may be resorted to without departing from the spirit of the invention, and the language used in the specification should not be construed in a limited sense. The breadth of the invention should only be considered in view of the structure set forth in the appended claim.

Referring more particularly to the attached drawings, wherein Figure 1 is a longitudinal section taken on line A—A, Fig. 2; Fig. 2 is an end elevation, and Fig. 3 is a side elevation. Like letters of reference indicate similar parts throughout the several views, in which 1 and 2 represent

head and foot sections respectively of a bed, these sections are connected by side rails 3. Upon these side rails 3 the usual spring 55 structure as indicated at 4 is supported and on the spring a mattress 5 as is the general custom. All of the structure so far recited is of any conventional form.

Supported between the side rails 3 of the bed is a heated element which in the present instance is illustrated as a boxing or pan 6 having a tapered bottom wall and provided with a compartment 7 in which an electric gas or other heater may be located. Outlets 60 8 are for delivering the heated air to the foot portion of the bed. The compartment 7 may be perforated as at 9 to provide an air inlet.

An arched framework as illustrated at 10 is supported by the side bars and extends 70 from one to the other above the mattress 5.

This framework is made of crossed strips 11 of metal, fiber, wood or any other material and is covered with cloth, silk, etc., 11'. The foot end of the arched member is closed by 75 the covering over the same, while at its head end it is provided with an extension 12 to be used by the person to cover the upper portion of the body.

In order that a free circulation may be 80 maintained within the covered frame a valve member 13 is attached preferably in the top portion of the same.

It will be readily understood that in cases of sickness when the regulation of the temperature to which the body is subjected, plays an important part, this device will accomplish the desired results. Also in cases of children who have a tendency to kick the covers from their body and thereby expose 90 themselves to colds, etc., this device is highly efficient as the covers are freely supported above the body and therefore afford a freedom of movement beneath the arched frame.

As both the heating element and the 95 arched frame have no positive connection with the bed, they can easily be detached from one bed and placed in position on another for any reason whatsoever.

What I claim:

The combination of a bed frame, air heating means consisting of a heating pan secured to the bottom of the bed having a

tapering bottom wall and having a compartment adapted to house a suitable heater, a spring and mattress above said pan, the said tapering wall having a portion extending beyond the end of the spring and mattress forming an outlet for directing heat above the mattress and a removable superstructure for confining the heat above the

mattress and a vent for regulating the amount of heat within the superstructure. 10

In testimony whereof I affix my signature in the presence of two witnesses.

RUDOLPH FERENTZI.

Witnesses:

PHILIPP CRAMER,
M. M. DENBIGH.
